UNITED STATES PATENT OFFICE

JEREMIAH J. O'NEIL, OF WINCHESTER, MASSACHUSETTS, ASSIGNOR TO CONVERSE RUBBER COMPANY, OF MALDEN, MASSACHUSETTS, A CORPORATION OF MASSACHUSETTS

DESIGN FOR A SHOE SOLE

Application filed October 18, 1930. Serial No. 37,309. Term of patent 3½ years.

To all whom it may concern:

Be it known that I, JEREMIAH J. O'NEIL, a citizen of the United States of America, residing at 3 Sachen Road, in Winchester, county of Middlesex and Commonwealth of Massachusetts, have invented a new, original, and ornamental Design for Shoe Soles, of which the following is a specification, reference being had to the accompanying drawings, forming a part thereof.

In said drawings:

Fig. 1 is a plan view of a shoe sole showing my new design; and

Fig. 2 is a section on the line 2—2 of Fig. 1.

I claim:

The ornamental design for a shoe sole substantially as shown.

Signed by me at Malden, in the county of Middlesex, and Commonwealth of Massachusetts, this third day of October, 1930.

JEREMIAH J. O'NEIL.
